UNITED STATES PATENT OFFICE.

ALFRED BARTH, OF MILWAUKEE, WISCONSIN, ASSIGNOR TO ROBERT J. ROSE, OF MILWAUKEE, WISCONSIN.

SLICING-MACHINE.

No. 910,635.

Specification of Letters Patent.

Patented Jan. 26, 1909.

Application filed September 12, 1908. Serial No. 452,783.

To all whom it may concern:

Be it known that I, ALFRED BARTH, a citizen of the United States, and resident of Milwaukee, in the county of Milwaukee and 5 State of Wisconsin, have invented certain new and useful Improvements in Slicing-Machines; and I do hereby declare that the following is a full, clear, and exact description thereof.

10 My invention consists in certain peculiarities of construction and combination of parts hereinafter particularly set forth with reference to the accompanying drawings and pointed out in claims; its object being to provide simple, economical and effective light-running, variable feed machines for slicing bread, meats, vegetables and other food-stuffs; these machines being especially designed for the butcher, grocery, hotel and 20 restaurant trade.

Figure 1 of the drawings represents a sectional side elevation of a slicing machine in accordance with my invention; Fig. 2, a plan view of the same having parts thereof in 25 horizontal section; Fig. 3, a transverse section view of the machine indicated by lines 3—3 in Fig. 1, and Fig. 4, a similar view indicated by lines 4—4 in Fig. 2.

Referring by letter to the drawings, A indicates a base provided with standards B adjacent to its corners. The upper ends of the standards are fashioned to constitute bearings for parallel shafts C provided at 30 their ends with cranks D, E, said cranks of each shaft being at a right-angle to one another. The base is also provided with guides F for shoes G upon the underside of a cutting-board H, and a rack I is attached to a longitudinal edge of the board. The 35 other longitudinal edge of the board is provided with a socket b for a post J that engages an eye-end of a clamp-arm K, and a set-screw c is employed to bind the arm in vertically adjusted position on the post.

40 The upper end of another standard L on the base A is provided with bearings for a rock-shaft M having a crank N in pivotal connection with a pawl O engageable with the rack aforesaid. Another crank P of 45 the shaft M has an eye-end engaged by a screw d having an adjusting nut e thereon, and a spiral spring Q connects the screw with a screw-eye f or other suitable fastening device with which the aforesaid base is provided.

55 Set in an upper recess g of the crank P is a

plate R having a bevel end h and a longitudinal slot i, which slot is engaged by a plate-binding set-screw j with which said crank is provided. The bevel end of the plate R is in the path of a similar end k of a wiper S 60 secured by a set-screw m or otherwise on one of the shafts C, and the throw of the pawl C is determined by the adjustment of said plate. Arranged in connection with an arm n of the standard L is a stop-screw p in opposition to the crank P, and by means of a set-nut q thereon, the stop-screw is held in adjusted position.

The front of the base A is provided with guides S' for a slicing knife T having eyes engaged by collars r of rods s constituting arbors for handles U, and these arbors are adjustably secured in longitudinal slots of the cranks D by means of set-nuts u, said slots permitting adjustment of the knife to compensate for wearing away of the same at its edge. One of the slots is shown at t in Fig. 3.

A bar V is employed in connection with the cranks E to balance the knife and to prevent sticking of the same on dead-centers. 80

The material to be cut is held on the cutting-board H by an adjustment of the clamp-arm K vertically of the post J, said cutting-board being then run back on its guides. The thickness of the slices to be cut is determined by the set of the plate R to regulate the throw of the pawl O in engagement with the rack I of the cutting-board. When the wiper S is in contact with the plate R, the slicing knife is elevated above the material to 90 be cut, and during the contact of said wiper with said plate the shaft M is rocked against resistance of the spring Q to slip the pawl O the predetermined distance on the rack I, and when said contact is broken, the contraction of said spring results in a reverse rock of 95 said shaft to effect a forward feed of the cutting-board and material thereon under the descending knife, said cutting-board and material being stationary when the cut of the 100 knife takes place.

I claim:

1. A slicing-machine comprising a base and standards thereon, a pair of parallel shafts for which certain of the standards are 105 provided with bearings, cranks on opposite ends of each shaft, the set of the cranks being at right-angles to one another; a knife in connection with the cranks at one end of the machine, and a bar connecting the cranks at the 110

opposite end of said machine; a bevel-end wiper attached to one of said shafts, a cutting-board guided on the base and provided with a rack, a rock-shaft for which a standard on the base is provided with bearings, a rack-engaging pawl in crank-connection with the rock-shaft, a spring connecting said base and a crank of the rock-shaft, and a bevel-end plate adjustable in connection with the latter crank to come in the path of said wiper.

2. A slicing-machine comprising a base and standards thereon, a cutting-board guided on the base and provided with a rack, a post in connection with the cutting-board, and a clamping-arm having vertically adjustable connection with the post; parallel shafts for which certain of the standards are provided with bearings, cranks on opposite ends of each shaft, the set of the cranks being at right-angles to one another; a knife in con-

nection with the cranks at one end of the machine, and a bar connecting the cranks at the opposite end of said machine; a bevel end wiper attachable to one of said shafts, a rock-shaft for which a standard on the base is provided with bearings, a rack-engaging pawl in crank-connection with the rock-shaft, a spring connecting said base and a crank of the rock-shaft, and a bevel-end plate adjustable in connection with the latter crank to come in the path of said wiper.

25
30
In testimony that I claim the foregoing I have hereunto set my hand at Milwaukee in the County of Milwaukee and State of Wisconsin in the presence of two witnesses.

ALFRED BARTH.
